CIRCUIT INTERRUPTER

Anthony Van Ryan, South Milwaukee, Wis., assignor to McGraw Electric Company, a corporation of Delaware

Application June 6, 1947, Serial No. 753,016

4 Claims. (Cl. 200—109)

1

This invention relates to circuit interrupters and is an improvement over the invention disclosed in my copending application, Serial No. 546,245, filed July 24, 1944, now Patent No. 2,448,695, Sept. 7, 1948, for Circuit Breakers and assigned to the same assignee as this invention.

In general, this invention has the same objects as those set forth in my above noted copending application.

In my copending application, over-center toggle link mechanism was employed and the circuit interrupter was automatically tripped by breaking the toggle link mechanism. The present invention retains the toggle link mechanism but employs a novel means of holding the toggle link mechanism extended, though not over-center, under normal conditions, and provides means for releasing the toggle link mechanism so that it can collapse and allow automatic opening of the circuit interrupter.

Further objects of this invention are to provide latch means for normally locking the toggle link mechanism in extended condition and arranged to automatically release the latch means to allow collapse of the toggle link mechanism and opening of the circuit interrupter on over-load thereby securing a more precise point at which the toggle link mechanism will collapse and requiring less force for its release.

An embodiment of the invention is shown in 30 the accompanying drawings, in which:

Figure 1 is a vertical sectional view partly broken away through the circuit interrupter, such view corresponding to a section on the line 1—1 of Figure 3.

Figure 2 is a sectional view on the line 2—2 of Figure 1, such view being partly broken away.

Figure 3 is a view partly broken away and partly in section looking down on the circuit interrupter. In this view the lower portion of the mechanism has been omitted for clearness.

Figure 4 is a fragmentary sectional view on the line 4—4 of Figure 1.

Figure 5 is a fragmentary view partly in section and partly broken away showing the circuit interrupter in open position.

Figure 6 is a fragmentary view of an intermediate position that the parts take during automatic opening of the circuit interrupter.

Figure 7 is a fragmentary view showing the position of the parts while the manipulating handle is being moved towards manual opening position.

Figure 8 is a fragmentary view showing the position of the parts when the circuit interrupter has been opened.

2

Referring to the drawings, it will be seen that the circuit interrupter is mounted within a tank or can 1 having closed bottom and side walls terminating in a beaded upper edge indicated at 2. The tank is closed by means of a top or cover 3 which has a gasket 4 resting upon the beaded edge 2 of the lower portion of the tank. The tank is provided with a bracket 5 of any suitable type, whereby it may be attached to a pole or other support in the usual manner. The top is held to the tank by any suitable means, as by means of the bolts 6 and nuts 7. Insulating bushings 8 extend downwardly into the tank and below the oil level as indicated and carry terminals, not shown, at their upper ends in accordance with the usual practice. The tank is preferably lined with a fiber lining 9.

The entire circuit interrupter is supported from the cover 3. Insulating tubular members 10 attached to the cover in any suitable manner extend downwardly and receive the bolts 11 by means of which the insulating portion 12 of the contact assembly is held in place. This insulated section may take any suitable form. It is preferably provided with side walls 13 between which the movable and stationary contacts are positioned. The stationary contacts are indicated by the reference character 14 and the movable contacts by the reference character 15. The movable contacts are carried by metal arms or levers 16 which are pivoted at 17 and are provided with metal spacers 18 against which the ends of a U-shaped bronze or other metal conducting member 19 bears. The inner ends of the arms 16 are slotted as indicated at 20 and receive the pin 21 carried by the insulating slide rod 22. When the switch is in closed position the parts are as shown in Figure 2. In order to open the switch, the slide rod 22 is pulled upwardly by means hereinafter described and suddenly separates the movable contacts from the stationary contacts and rocks the levers or arms 16 downwardly into contact with the insulating bushings or spacers 23 for the lower portion of the side walls 13, and thus limits the upward travel of the slide rod 22 as well as the downward rocking motion of the movable contacts 15, see Figure 5. A pair of tension springs 24 are connected to a transverse pin 25 at their lower ends and at their upper ends are anchored to the top 3 of the casing. These springs, therefore, constantly pull upwardly on the slide rod 22. The pin 25 serves to pivot the lower arm 26 of a toggle link mechanism, the upper arm of such toggle link mechanism being indicated at 27, the arms being pivotally joined together as indicated

at 28. In reality, the arm 26 consists of a pair of links as shown most clearly in Figure 2 located on opposite sides of the slide bar 22. A small latch 29 is pivotally carried by the lower arm or arms 26 of the toggle link and normally latches a downwardly projecting extension 30 of the upper arm 27 of the toggle link mechanism. The latch 29 is spring urged as indicated at 31 in a counter-clockwise direction and is provided with an extension or trip engaging portion 32. The upper end of the arm 27 rigidly carries a pin 33 which is pivotally mounted in one of the arms 34 of a bell crank lever, the other arm of such bell crank lever being indicated by the reference character 35.

It is to be noted that the pin 33 is diametrically cut away at one end and the remaining half of the pin bears against a shoulder 36 formed on a latch lever 37. The latch lever 37 is urged in a clockwise direction by means of the spring 38. It is provided with an extension or foot 39 at its lower end. The bell crank lever 34, 35 is provided with an upwardly projecting arm 40 which is connected to one end of a spring 41, such spring being anchored at its other end to the cover 3, as shown in Figure 1. The bell crank lever is, therefore, urged in a counter-clockwise direction. It is loosely mounted on a rock shaft 42 journaled in any suitable manner in the cover 3 and projecting outwardly from one side of the cover and is provided with a manipulating eyeleted arm 43 adapted to receive a switch stick. Normally, this arm is housed in a downwardly opening casing 44 carried by the cover 3 and may be reached by the hook end of a switch stick so that the arm may be pulled downwardly to manually open the circuit interrupter or pushed upwardly to reset the circuit interrupter. A lever or arm 45 is rigidly mounted on the rock shaft 42, see Figure 1, and is connected by means of a spring 46 with the arm 35 of the bell crank lever heretofore described.

The spring 46 holds a foot or extension 47 of the lever 45 in engagement with the under side of the arm 35 of the bell crank lever. The lever or arm 45 is provided with an extension 48 which, when the rock arm or manipulating arm 43 is pulled downwardly, is adapted to engage the foot 39 of the latch lever 37 and move such latch lever to the right as viewed in Figures 1 and 7 to disengage the pin 33 from the shoulder 36, and allows the springs 24 to raise the slide bar 22 and thus suddenly open the circuit interrupter.

On the other hand, provision has been made for the automatic opening of the circuit interrupter as by manipulating the extension 32 of the latch 29 so that on overload the latch 29 will be released and the toggle link mechanism will be allowed to collapse temporarily, thus allowing the springs 24 to suddenly open the switch. The toggle link will straighten itself out at the upper end of its stroke for it will be seen that the flattened face of the pin 33 will rock and will thus force the latch 37 clear of the pin and allow the arm 34 of the bell crank lever to rock upwardly under the influence of the spring 41 and will thus again straighten out the toggle link mechanism as upward motion of the lower end of the toggle link mechanism is prevented when the switch arms 16 strike the spacers or stops 23, see Figure 5, in the manner hereinbefore described. Figure 6 shows the toggle link mechanism as it is collapsing and Figure 8 shows the toggle link mechanism straightened out or ex-

tended. This automatic straightening out or restoring of the toggle link mechanism to its normal condition occurs while the movable and stationary contacts remain separated.

5 When the circuit interrupter is opened either by automatic or manual operation, the arm 43, see Figure 2, rocks downwardly into a displayed position. In resetting, the lineman engages the arm 43 with the switch stick and forces the arm upwardly, thus rocking the rock shaft 42 in a clockwise direction. The arm or lever 45 rigid with such rock shaft engages the under side of the lever 35 and forces the lever 35 upwardly, thus depressing the arm 34 of the bell crank 10 lever and moving the circuit interrupter back into closed positon. Obviously, at any time during this closing motion, the automatic means herein-after described can trip the latch 29 by engaging the extension 32 in the event overload still 15 persists.

The condition responsive means or overload means for automatically tripping the circuit interrupter may take any desired form; for example a solenoid consisting of a spool-like member 48 20 provided with an energizing winding 49 may be employed to draw a magnetic plunger 50 upwardly into the cylindrical chamber 51. It is preferable to provide an encircling yoke or frame 52 of magnetic material and to provide a downward extension or guiding sleeve 53, preferably of nonmagnetic material, for normally receiving the magnetic plunger 50, this sleeve being open at its bottom and a pin 54 being provided to determine the lower limit of the downward stroke 30 of the magnetic plunger 50. The upper end of the magnetic plunger 50 is preferably tapered as indicated at 55 and a magnetic upper pole piece 56 located in the upper end of the chamber 51 is bored out or internally tapered corresponding to the upper tapered nose 55 of the magnetic plunger 50. It is preferable to slot the lower end of the upper pole 56 and the upper end of the magnetic plunger to reduce eddy currents. A pin 57, preferably of nonmagnetic material, extends through the upper pole 56 of the solenoid and is provided with a small collar 58 which is received in a cylindrical portion 59 in the upper pole 56.

The solenoid may be supported in any suitable 50 manner from the lower assembly or insulating housing 12; for example, an insulating bracket 60 may be secured to the housing 12 and may support the solenoid. An insulating trip member or lever 61 is pivoted as indicated at 62 and its center of gravity is to the left of the pivot point so that it tends to remain in the position shown in Figure 1 under normal conditions. This trip member 61 is adapted to be rocked in a clockwise direction on overload when the pin 57 55 is moved upwardly in a manner hereinafter described. Clockwise motion of the trip member 61 or lever causes it to engage the extension 32 of the latch 29 and to thus release the latch and allow automatic opening of the circuit interrupter to occur.

Assume that a heavy overload occurs. Under 60 these conditions the magnetic plunger 50 starts upwardly suddenly and places the oil in the cylindrical chamber 51 under very heavy pressure, it being understood that the entire solenoid is submerged in the oil contained in the casing 1 as indicated in Figure 1. This heavy pressure drives the pin 57 upwardly and rocks the trip member 61 and thus causes automatic opening of the circuit 70 interrupter. On the other hand, suppose that an

overload occurs just sufficient to cause upward travel of the plunger 59. Upward travel of the plunger 59 is delayed due to the time delay action of the oil in the cylindrical chamber 51. The displaced oil has to leak around the plunger or armature 50 as the armature moves upwardly and consequently a time delay is provided. As the air gap is shortened between the upper end of the plunger 59 and the upper pole piece 56, the pull on the plunger increases very greatly and the oil pressure above the plunger correspondingly increases. This oil pressure is sufficient under all but the very lightest overloads to at least finally move the trip pin 57 upwardly and cause automatic opening of the circuit interrupter. On extremely small overloads the upper end of the plunger 59 actually engages the pin 57 and causes automatic opening of the circuit interrupter.

It is to be noted that the cylindrical portion 59 is closed at its upper end by the insulating bracket 60 except for the difference in diameter between the pin 57 and the hole through which it extends. The purpose of this construction is to have the collar 58 and the cylinder 59 form a shock absorbing hydraulic means so that high currents of short duration, such as caused by lightning surges, will not trip the circuit interrupter. A short time delay is thus provided for the pin 57 so that high current values will have to be maintained for a short time before a trip action can occur.

It will be seen that this invention provides a novel form of circuit interrupter in which a very small amount of force is required to operate the latch and allow automatic collapse of the toggle link mechanism. The point at which tripping occurs is precisely determined by the latch.

Further it will be seen that after collapse of the toggle link mechanism it is automatically again straightened out and ready to be moved downwardly when the circuit interrupter is manually reset as described hereinabove.

It will be seen that the mechanism of the circuit interrupter is simple and reliable in its operation and positively determines the exact point in the motion of the parts at which tripping will occur.

Although this invention has been described in considerable detail, it is to be understood that such description is intended as illustrative rather than limiting, as the invention may be variously embodied and is to be interpreted as claimed.

I claim:

1. A circuit interrupter comprising stationary and movable contact means, means biasing said movable contact means away from said stationary contact means, toggle link mechanism arranged when extended to hold said movable contact means in engagement with said stationary contact means, a latch for locking said toggle link mechanism in extended condition, condition responsive means for tripping said latch to allow collapse of said toggle link mechanism, reset means for closing said circuit interrupter, and automatic means arranged to extend said toggle link mechanism after collapse thereof without closing said circuit interrupter, said automatic means being independent of said reset means.

2. A circuit interrupter comprising stationary and movable contact means, means biasing said movable contact means away from said stationary contact means, toggle link mechanism arranged

when extended to hold said movable contact means in engagement with said stationary contact means, a latch pivoted on one arm of said toggle link mechanism for locking said toggle link mechanism in extended condition before said toggle link mechanism has passed dead center, reset means for closing said circuit interrupter, condition responsive means for tripping said latch to allow collapse of said toggle link mechanism, and means independent of said reset means for extending said toggle link mechanism after collapse thereof.

3. A circuit interrupter comprising switch means, normally extended toggle link mechanism having a first arm and a second arm, said second arm having its outer end connected to said switch means, holding means normally holding the outer end of said first arm against motion of translation, means biasing said switch means towards opening motion and biasing said toggle link mechanism towards motion of translation, a latch carried by one arm of said toggle link mechanism for holding said toggle link mechanism extended when said toggle link mechanism is close to dead center but before said toggle link mechanism has passed dead center, condition responsive means for tripping said latch to allow collapse of said toggle link mechanism and opening of said switch means, and means for releasing said holding means to cause opening of said switch means without collapse of said toggle link mechanism.

4. A circuit interrupter comprising switch means, normally extended toggle link mechanism having a first arm and a second arm, said second arm having its outer end connected to said switch means, a first latch normally holding the outer end of said first arm against motion of translation, means biasing said switch means towards opening motion and biasing said toggle link mechanism towards motion of translation, a second latch carried by one arm of said toggle link mechanism for holding said toggle link mechanism extended, condition responsive means for tripping said second latch to allow collapse of said toggle link mechanism and opening of said switch means, means arranged to detach said first latch from said first arm upon collapse of said toggle link mechanism, means for automatically extending said toggle link mechanism after detachment from said first latch, and manually operable means movable in one direction to detach said toggle link mechanism from said first latch to open said switch means and movable in the other direction to close said switch means and cause re-engagement of said toggle link mechanism and said first latch.

ANTHONY VAN RYAN.
